UNITED STATES PATENT OFFICE.

VINCENT P. BUDNIK, OF GRAND RAPIDS, MICHIGAN.

CARPENTER'S HAMMER.

1,331,619.

Specification of Letters Patent. Patented Feb. 24, 1920.

Application filed April 1, 1918. Serial No. 226,109.

To all whom it may concern:

Be it known that I, VINCENT P. BUDNIK, a subject of Russia, having first papers as citizen of the United States, residing at 5 Grand Rapids, in the county of Kent and State of Michigan, have invented certain new and useful Improvements in Carpenters' Hammers, of which the following is a specification.

10 My invention relates to improvements in carpenters' hammers, and its objects are: first, to provide a means whereby nails may be carried upon the handle of the hammer in position to be readily available for driving into any desired wood construction; second, to provide a nail holder with which the nails may be, automatically, removed from the holder and placed in position at the face of the hammer head so that with a 15 stroke of the hammer the nail will be started in the material into which it is to be driven; third, to provide a means whereby the movement of the nail from the holder to the face of the hammer head will be positive and uniform at all times; fourth, to so arrange the nail carrying vise that it will relieve the nail and return into normal position to receive another nail as soon as the nail has been properly started and the vise released, 20 and, fifth, to provide a means whereby the movement of the nails from the holder into position to be engaged by the carrying clamp or vise will be positive and certain, no matter what position the hammer may be held in.

25 I attain these objects by the mechanism and construction of parts shown in the accompanying drawing, in which Figure 1 is an elevation of the front side of a hammer with my holder in place. Fig. 2 is a back 30 elevation of the same. Fig. 3 is a bottom plan of the same. Fig. 4 is a sectional view of the hammer handle on the line 4—4 of Fig. 1, showing an end elevation of the holder in normal position thereon. Fig. 5 is a sectional elevation of the holder looking to the left from the line 5—5 of Fig. 6. or back of which the arm 10 passes. This arm is made integral with the lever 9 and has an offset at *e* so that normally the lever 11 will stand in position for the free passage of a nail onto the ledge *h*. It will be noticed, by reference to Figs. 1 and 8, that there is a free space between the head of the connecting rod 7 and the lug on the lever 8 so that a slight movement of the lever will be allowed at *d* before the disk 5 will be affected thereby.

The disk 5 is loosely mounted upon the shaft *i* and is held in position to hold the arms 4 and 13 in normal position by means of an available form of spring, as 6, anchored at one end to the disk, and at the other end with the shaft support 3', as at *g*.

The operation of this implement is as follows: When the lever 9 is moved into the position indicated by the dotted lines *g* Fig. 8 the arm 10 Fig. 1 is forced far enough endwise to carry the offset *e* under the roller 12 and force this end of the lever 11 outward far enough to carry the other end against the side of a nail 16 and shove the nail sideways against the springs 15, far enough to enter between the vise jaw 17 and the vise arm 4. This just closes the gap *d*. The movement of the lever 9 into the position indicated by the dotted lines *h* will draw upon the connecting rod 7 sufficiently to force the arm 13 against the back, or outer end of the vise jaw 17, clamping the nail firmly between the vise jaw and the end of the arm 4, and the movement of the lever 9 into the position indicated by its dotted lines in Fig. 1 will move the connecting rod 7 sufficiently to revolve the disk 5 and carry the arms 13 and 4 into the position indicated by their dotted lines in Fig. 1, with the head of the nail resting against the face of the hammer, as hereinbefore intimated, where a stroke of the hammer will insert the nail into any penetrable substance against which the nail may be driven, sufficiently to hold it while driving it to its limit, when the loosening of the lever 9 to drive the nail further releases the nail from the vise and allows the arms 13, 4 and 11 to assume their normal positions. The levers 4 and 13 being carried back by the spring 6, and the lever 11 being carried back by the spring 11'.

o, in Fig. 8, indicates the manner of connecting the rod 7 with the disk 5, and *p*, Fig. 7 indicates how the springs 15 may be connected with the back of the receptacle.

For the purpose of readily attaching the implement to, or removing it from the hammer handle, I find it advisable to form hinges, as 14, on the back of the receptacle, as indicated in Fig. 2. *f* represents the pivotal connection of the lever 8-9 with the supporting elements of the nail receptacle.

What I claim as new in this art, is:

1. In combination with a hammer and a hammer handle, a nail receptacle having a broad entrance part and a narrow discharge part, said discharge part having an open slot through the back wall at the extreme end thereof, a lever pivotally mounted opposite this slot, a shaft revolubly mounted near one end and back of the receptacle, a vise arm mounted on said shaft, a disk mounted on the shaft adjacent to the vise arm, an arm made integral with said disk, a vise jaw pivotally mounted upon the end of the vise arm in position to be actuated by the disk arm, a spring for holding the vise arm and the integral disk arm in normal position, a main lever pivotally mounted upon the receptacle frame, a connecting rod connecting the main lever with the disk, an arm passing from the main lever to the vise arm arranged to actuate the vise arm to transfer a nail through the slot in the receptacle between the vise jaws, all arranged so the movement of the main lever will transfer a nail from the receptacle into the vise and thence to the head of the hammer at right angles with the face thereof. 90

2. In combination with a hammer and hammer handle, a receptacle for nails, said receptacle firmly clamped upon one side of the hammer handle and having a large intake part above the hammer handle and a narrow discharge part below the hammer handle for holding and delivering nails, a cover and spring on said receptacle for holding the nails in position in the receptacle at an acute angle with the edge of the hammer handle and the hammer head, and means for clamping the nails by the heads and transferring them from the receptacle into position at right angles with the face of the hammer head, substantially as shown 100 and described.

3. In combination with a hammer and hammer handle, a nail receptacle securely attached to one side of the handle and extending slightly above and below the edges 110 of the handle, and arranged to hold the nails *en masse* and at a slight angle with the handle and with the side of the hammer head, means in said receptacle for holding the nails in uniform position and for forcing them to a point of delivery, means for clamping the heads of the nails at the point of delivery and carrying the nails so the surface of the heads of the nails will bear upon the face of the hammer head with the nails extending directly out at right angles with the face of the hammer head, and means for releasing the nails when set. 120

Signed at Grand Rapids, Michigan March 26, 1918.

VINCENT P. BUDNIK.
